[57] CLAIM

The ornamental design for an automobile bumper, as shown.

DESCRIPTION

FIG. 1 is a perspective view of an automobile bumper showing the new design;

FIG. 2 is a front elevation view thereof;

FIG. 3 is a top plan view thereof;

FIG. 4 is a bottom plan view thereof; and

FIG. 5 is a right side elevation view thereof, it being understood that the left side elevation view is a mirror image thereof of that shown.

FIG. 1

FIG. 5

FIG. 3

FIG. 2

FIG. 4
